JOINTED SHOE SOLE

Julius Baer, Beverly Hills, Calif.

Application July 5, 1943, Serial No. 493,529

4 Claims. (Cl. 36—33)

This invention relates to the construction of a sole of a shoe. On account of the present industrial requirements, restrictions have been placed on the use of materials ordinarily used for shoe soles, as a consequence of which it is necessary to make shoe soles of other materials, and for this purpose wood is a convenient and available material. But, of course, wood has the objection of rigidity if constructed of the thickness usually employed in shoe soles.

It has been suggested heretofore to overcome the objection of rigidity in using wood for shoe soles, by employing one or more joints in the construction of the sole, that enable the sole to flex at one or more lines or axes extending transversely to the sole. Many specific constructions have been suggested to be employed in the manufacture of such a joint, but many of them require the use of some metal parts in their construction; and, furthermore, they are generally constructed so that the sections of the sole that are jointed together, cannot be readily separated without the use of special tools.

One of the objects of the present invention is to provide a shoe sole having a transverse joint, or joints, so constructed as to adapt the sole to be constructed of a rigid material such as wood, or similar material.

Another object of the invention is to provide a shoe sole adapted to be constructed of wood, or similar material, and having a joint constructed so as to enable the parts to be readily separated at the joint, thereby enabling a worn toe portion of a shoe sole to be discarded, and a new toe portion attached in place, without necessitating the employment of special tools for this purpose.

Another object of the invention is to produce a sole particularly adapted to be constructed of a rigid material such as wood, and having a joint permitting a limited amount of flexing of the sole in walking, and in which all the parts at the joint can be constructed of the same material such as wood.

Further objects of the invention will appear hereinafter.

The invention consists in the novel parts and combination of parts to be described hereinafter, all of which contribute to produce an efficient jointed shoe sole.

A preferred embodiment of the invention is described in the following specification, while the broad scope of the invention is pointed out in the appended claims.

In the drawing:

Fig. 1 is a plan view and partial section illustrating the shoe sole embodying my invention.

Fig. 2 is a longitudinal section taken about on the line 2—2 of Fig. 1, and further illustrating details of the construction illustrated in Fig. 1.

Fig. 3 is an edge view showing the edge of one

of the articulated portions of the shoe sole illustrated in Fig. 1.

Fig. 4 is a similar edge view of the articulated edge of the other articulated part of the shoe which, in the present instance, is the heel portion.

Before proceeding to a more detailed description of the invention, it should be stated that in the present specification and drawing, I have described and illustrated a shoe sole having a single joint, but in practice if desired, two or more such joints may be employed.

In practicing the invention I provide a sole 1 which, in the present instance, is composed of two portions including a heel portion 1a and a toe portion 1b. These two portions 1a and 1b are articulated or jointed together by means of a joint 2. The joint 2 is formed by providing one of the meeting edges of these two parts 1a and 1b with a concave socket. In the present instance, I provide the rear edge of the toe section 1b with a concave socket 3 which is a cylindrical face having its axis at the point 4, but this face 3 is not continuous but is broken through by means of a tongue 5 that is disposed at about the medial horizontal plane of the toe section 1b, and which projects toward the heel section 1a. This tongue 5 may be made integral with the toe piece 1b, or it may be made if desired, as a separate part mortised at its root into the part 1b, as will be readily understood by wood-workers.

The adjacent face or forward edge of the heel portion 1a is formed with a convex face 6, which also has its axis at the point 4 as indicated in Fig. 2, so that this forward edge of the part 1a can socket itself and fit nicely into the socket 3.

The forward portion of the heel portion 1a is formed with a transversely extending socket in the form of a bore 7, which also has its axis at the point 4, and the tongue 5 is provided at its outer portion with a bolster or tenon 8 which is in the form of a cylindrical pin that fits neatly so as to socket itself in the bore 7. While this tenon 8 may if desired, be formed as an integral part 40 of the tongue 5, in the present instance this tenon is made of a separate piece of wood with the grain running longitudinally of the tenon. Likewise, the grain in the tongue 5 preferably extends in the direction in which the tongue extends, that is to say, in a front and rear direction with respect to the shoe sole. If the tenon 8 is constructed as a separate piece, it should be provided with a slot on one side to fit closely as a socket on the end portion of the tongue, and may be secured to the same by glue, or other means.

The outer wall of the cylindrical socket 7, that is to say, the wall 9 that is disposed adjacent to the socket 3, is formed with a slot 10 that extends transversely to the sole, and this slot

has a width that is slightly greater than the thickness of the tongue 5, so that a slight clearance space or lost motion space 11 is formed in the joint near the root of the tongue 5. The edges of this slot act as stops to limit the flexing movement in both directions.

In constructing this joint, the axis of the joint indicated at the point 4, is preferably located about in the medial "plane" between the upper face 12 of the shoe sole and its lower face 13; and at the under side I may form two diverging beveled shoulders 14. This will prevent the nap of carpet, or dirt, from being pinched between these shoulders. The clearance space 11 between the edges of the slot 10 and the tongue 5, will permit a limited flexing movement of the toe portion 1b in walking.

At the upper portion of the joint the rear and upper portion of the toe portion 1b is preferably formed with a relieved edge 15; in other words, the arc or cylindrical surface 6 is substantially tangent to the upper face 12 at this point. My purpose in constructing the upper side of the joint in this way, is to avoid forming shoulders on the upper side between which the sock liner of the shoe or the material of a stocking could be pinched.

As illustrated in Fig. 1, the bore 7 extends into the edge of the sole from one edge only, and in this way a transverse wall or head 16 is formed near the opposite edge of the sole, which operates as a stop when the two portions of the sole are assembled. However, a slot 17 is formed through this head, of a slightly greater width than the tongue 5, so as to permit the edge portion 18 of the tongue (see Fig. 1) to fit into this slot 17 when the parts are assembled; and the assembling of these parts may be accomplished by inserting the end 19 of the bolster in the mouth of the bore 7, and then shifting the toe portion laterally with respect to the heel portion. This will cause the bolster or tenon 8 to telescope into its socket 7. This telescoping movement will continue until the inner end of the bolster 8 comes up against the inner face of the wall or head 16. At the other end of the bolster the tongue 5 and the end face of the bolster are flush with each other as illustrated in Fig. 1.

It is most advantageous to have the parts of this sole constructed as described, because in practice, most of the wear will occur on the toe portion 1b, and when this portion becomes worn it can be readily disconnected, and a new toe portion having the same construction, substituted.

Wooden soles constructed as described, are of course inexpensive due to the fact that they can be constructed of wood, or similar material, and also on account of the fact that the operations necessary to form the joint, are very simple and easily performed.

This sole can be used in the construction of other shoes if desired, or for sport shoes or sandals, or for any other kind of footwear.

In practice, if desired, the stop wall 16 can be placed at the inner edge of the sole instead of at the outer edge as illustrated in Fig. 1. Furthermore, if this sole is employed with a sandal type upper that does not provide means for covering the outer end of the joint (at the edge opposite the wall 16), a mudguard or strip of flexible material such as leather, can be worked along the edge of the sole at this point.

In adapting the sole to special requirements of any purchaser, it will be evident that if the wearer of the shoe desires a greater amount or degree of flexing at the joint, the amount of the flexing can be increased by widening the slot 11, by cutting back its upper or lower edge.

As all of the contacting curved faces that compose the joint, have the same axis at the point 4 (as viewed in Fig. 2), it will be evident that this joint provides a true socket joint connection between the two parts of the sole.

Many other embodiments of the invention may be resorted to without departing from the spirit of the invention.

15. What I claim is:

1. In a shoe sole, the combination of two members having a joint connection between the same, one of said elements having a transverse meeting edge for the joint having a convex cylindrical surface with its transverse axis extending through said member, said member having a socket therein in the form of a bore disposed on the said axis, the wall of said bore on the side toward the other member having a slot therein; the other 20 of said members having a concave cylindrical face at its meeting edge operating as a socket for the said convex face, and having a tongue of less thickness than the width of said slot extending through the said slot into the said bore, said tongue having a cylindrical bolster at the inner end thereof, mounted to rock on its axis in the said bore, said slot and said tongue cooperating to permit flexing of said members at said joint to a limited degree.

2. In a shoe sole, the combination of two members having a joint connection between the same, one of said elements having a transverse meeting edge for the joint having a convex cylindrical surface with its transverse axis extending through

25 said member, said member having a socket therein in the form of a bore disposed on the said axis, the wall of said bore on the side toward the other member having a slot therein; the other 30 of said members having a concave cylindrical face at its meeting edge operating as a socket for the said convex face, and having a tongue of less thickness than the width of said slot extending through the said slot into the said bore, said tongue having a cylindrical bolster at the inner end thereof, mounted to rock on its axis in the said bore, said slot and said tongue cooperating to permit flexing of said members at said joint to a limited degree.

3. In a shoe sole, the combination of two members having a joint connection between the same, one of said elements having a transverse meeting edge for the joint having a convex cylindrical surface with its transverse axis extending through

35 said member, said member having a socket therein in the form of a bore disposed on the said axis, the wall of said bore on the side toward the other member having a slot therein; the other 40 of said members having a concave cylindrical face at its meeting edge operating as a socket for the said convex face, and having a tongue of less thickness than the width of said slot extending through the said slot into the said bore, said tongue having a cylindrical bolster embedding 45 the inner end thereof rigid with said tongue, mounted to rock on its axis in the said bore, said slot and said tongue cooperating to permit flexing of said members at said joint to a limited degree.

4. A shoe sole in accordance with claim 1, in

55 which the slot and the said bore extend in from a side edge of the sole, thereby enabling the said

members to be jointed together by moving one of

55 said members laterally with respect to the other

with the bolster and bore in line so as to telescope

60 with each other.

5. A shoe sole in accordance with claim 1, in which the slot in the said bore extends in from a side edge of the sole, thereby enabling the said

members to be secured together by moving one

65 of said members laterally with respect to the other

while telescoping the said bolster into the

65 said bore; the said bore having an end wall adjacent one edge against which the adjacent end of the bolster may abut to operate as a stop for the

70 lateral telescoping movement when the two members are in proper longitudinal alignment with each other.
